KNITTING MACHINE

Harry McAdams, Reading, Pa., assignor to The
Nolde & Horst Company, Reading, Pa., a cor-
poration

Application October 24, 1936, Serial No. 107,460

19 Claims. (Cl. 66—135)

This invention relates to improvements in knitting machines.

The primary object of the invention is the provision of improved means for automatically controlling and positioning the feed yarns of a knitting machine relative to the needles of the machine, so that the operation of placing the wrap yarns upon the needles may be efficiently carried out without much of the manual labor and extra operations now necessary.

10 A further object of the invention is the improved means for automatically lifting the yarn feed head assemblage of a knitting machine to an out of the way position relative to the needles, 15 at the end of the knitting of a stocking, or at any other desired interval during the knitting operation.

20 A further object of this invention is the provision of improved means, connected with the yarn feed head assemblage of a knitting machine, for automatically locating the yarns in position for effective placement upon the needles of the machine by the yarn feed fingers or members of the assemblage.

25 Other objects and advantages of this invention will be apparent during the course of the following detailed description.

30 In the accompanying drawings, forming a part of this specification, and wherein similar reference characters designate corresponding parts throughout the several views,

35 Figure 1 is a fragmentary side elevation of the improved machine showing the yarn feed head assemblage in feeding relation to the needles of the machine.

40 Figure 2 is a view similar to Figure 1, but with the yarn feed head assemblage elevated to an out of the way relation with respect to the hook ends of the needles of the machine, so as to permit the operator to have access to the fabric and needles of the cylinder, etc.

45 Figure 3 is a fragmentary vertical sectional view taken through the cylinder of the knitting machine and the adjacent associated features of the yarn feed head assemblage; showing the improved means associated with said assemblage for positioning and controlling the wrap or other yarns relative to the feed fingers and needles of the machine.

50 Figure 4 is a side elevation, partly in section, of the improved yarn controlling and guiding member.

55 Figure 5 is a partial bottom view of the improved yarn positioning and controlling member.

Figure 6 is a horizontal sectional view taken substantially on the line 6—6 of Figure 1.

In the drawings, wherein for the purpose of illustration is shown only a preferred embodiment of the invention, the letter A may generally designate the improved knitting machine, which may be generally of the type set forth in any of my following co-pending applications: Serial No. 591,689, filed February 8, 1932; Serial No. 662,354, filed March 23, 1933; Serial No. 703,483, filed Dec. 21, 1933.

10 The machine A may include a frame B; rotary cylinder C; a set of needles D for the cylinder C; a rotary bobbin head E; a vertically movable wrap yarn feed head assemblage F, which includes a movable frame G and the individual wrap yarn feed fingers H. The machine also includes the means J for automatically lifting the head assemblage F to an out of the way relation relative to the cylinder and needles of the machine at predetermined operations. Furthermore, the machine includes the improved means K in the nature of a plunger or extension of the head frame G and attached to the latter for controlling the position of the yarns relative to the hook ends of the needles D and the yarn feed fingers H, as will be subsequently described.

15 The details of the machine A, as above mentioned, are generally shown in my three above identified co-pending applications. The machine is of the rotary cylinder type, and of course it includes the usual swinging latch ring L, which is pivoted at 20 (see Figure 3 of the drawings). This latch ring L has the usual body yarn and other feed fingers associated therewith (not shown) and the said latch ring may further include the yarn restraining members 21, shown in Figure 3 which cooperate with the wrap yarn feed fingers H in restraining the yarn for feed upon the desired number of elevated needles, all of which is more specifically disclosed in my above 25 identified co-pending applications.

30 The frame B of the machine is provided with means for rotatably supporting the bobbin stand E, and this bobbin stand E is driven through 35 means 23, shown in Figure 1, and well understood in the art. The bobbin stand E preferably does not elevate or lower, but remains at one level, notwithstanding the fact that it is rotatable. On the other hand the yarn feed head assemblage F elevates and lowers relative to the bobbin stand, and relative to the cylinder C and the hook ends of the needles, in order that the feed fingers H may be placed into or out of feeding relation with the hook ends of the needles. Thus, the head as- 40

semblage F may include the shaft 25 which is splined to the rotary bobbin stand E. The shaft 25 at its upper end has the means J connected therewith for elevating and lowering the head 5 assemblage F automatically, as will be subsequently described.

The head frame G may be of any approved nature and is secured as at 27 to the shaft 25. The fingers H are fulcrumed in suitable slots or 10 by other suitable means upon the frame G, as more specifically disclosed in my above identified co-pending applications; these feed fingers H having apertured lower ends 30 for threading of the yarns therethrough. At their upper ends the 15 feed fingers H are provided with suitable butts 35, at different levels for operation by any of a group of cams 36, also placed at different levels. These cams 36, as shown in the drawings, are actuated by means 37 more specifically disclosed 20 in my above identified co-pending applications. The means 37 is pattern controlled off of suitable pattern drums 39 shown in Figures 1 and 2 of the drawings.

The bobbin stand E of course supports any 25 desired number of bobbins 40; the yarns of which are extended from the bobbins upwardly through suitable tensioners 41 and then thru spring take-up devices 42, shown best in Figure 2 of the drawings; the yarn being from this point 30 threaded downwardly through the head frame G and through the apertured ends 30 of the yarn feed fingers. Due to relative movement between the feed fingers and the bobbin stand as when the former is elevated and lowered, the take-up devices 42 keep the yarns 50 taut.

The means K for controlling the position of the wrap yarns 50 relative to the needles preferably consists of an extension axially connected to the head assemblage F with the lower end 40 thereof below the normal needle hook level when the head is lowered. In this position movement of the yarn feed fingers H to a needle feeding position will place the said yarns onto the needles. In detail the means K preferably includes 45 a shaft 60 detachably connected by a left hand screw thread 61 axially in the lower end of the shaft 25 or other part of the head frame G. The shaft K at its lower end has a preferably detachable yarn control head 63, of preferably 50 conical or frusto-conical shape, although the shape is irrelevant. It is peripherally grooved at 64, preferably with grooves disposed at an acute angle to the vertical so as to permit the yarns 50 to readily leave the grooves when the needles 55 catch the yarns which are fed by the fingers H to the needles. These grooves may take any form desired, however, and the head 63 may merely be roughened or provided with teeth or other means for holding the yarns in proper position.

It is to be noted that when the head F is lowered the member K holds the yarn in definite relation at a point below the hook ends of the needles, so that when the feed fingers H are 65 swung outwardly above the needles the yarns will be positioned for reception upon those needles intended to take them.

In the particular type of head shown, the fingers H are in circular arrangement and the member K is disposed within the circular arrangement.

It is customary practice on conventional machines embodying a wrapping head to tie all of the wrap yarns together in a knot prior to lowering the knitting head in position, and then to

hang a weight upon the knotted ends of the wrap yarns. This weight will pull the wrap yarns down into the cylinder and in position for feeding onto the needles when the wrap feed fingers are thrown into feeding position. The operator must perform this by hand with an attendant waste of time and effort. Thus, the operator not only has to hang the weight on the knotted ends of the yarns, but the operator also has to remove the weight from the stocking at the end of certain knitting operations in order to prevent the weight from slapping the stocking against some solid portion of the frame of the machine. The improved means K is entirely automatic in operation, and entails no move upon 15 the part of the operator except to knot together the ends of the yarns below the head end 63. Lowering of the head F will place the yarns in position for feeding to the needles upon movement of the respective yarn feed fingers. The 20 take-up springs 42 pull the yarns 50 taut beneath the head 63.

It is of course to be understood that I do not wish the invention limited to use upon a wrap yarn head type of knitting machine. The controlling member K may generally be used in connection with any yarn feeding apparatus for automatically or effectively controlling and placing the yarn in such relation that it will be fed to the needles of the machine at a desired movement of either a needle or yarn feed member. It could be used externally of the cylinder for that type of feed member which moves from the outside of the cylinder to the inside of the cylinder, and of course such control member could be used on flat knitting machines for holding the yarn in needle feed position at one side of the needle line while the yarn feed finger is swung to the opposite side of the needle line.

The improved means J for automatically lifting the yarn feed head H is pattern controlled off of one of the pattern drums. At its upper end the shaft 25, as shown in Figures 1, 2 and 6 of the drawings, is provided with a circumferentially grooved collar 80; in the grooves of which are 45 slidably disposed at diametrically opposed sides certain slide blocks or bars 81, pivoted upon a control yoke lever 82. The lever 82 is pivoted at 83 upon an extension 84 of the frame B. The pattern drum 39^a which controls the vertical movement of the yarn feed head operates a lever 85 which is pivoted at 86, and connected at 87 to another lever 88. The latter is pivoted at 89 on the frame of the machine. The lever 88 has a rod 90 which connects intermediate the ends 50 of another lever 91; the latter being pivoted at 92 on the frame of the machine. The lever 91 at its opposite end is attached by means of a connecting rod 93 with the end of the yoke lever 82 opposite the yoke end. With this leverage 55 mechanism a small cam throw of the drum 39^a will transmit a relatively long leverage movement to the yoke end of the lever 82, and thus raise and lower the yarn feed assemblage F between the position shown in Figures 1, 2 and 3 60 of the drawings.

Means is provided to lock the yarn feed head in its elevated position. This means consists of a spring operated detent 100 which engages the yoke lever 82 and holds the head F elevated, as shown in Figure 2 of the drawings. A handle lever 101 may be employed to release the detent 100 by pulling downward upon said handle.

From the foregoing it will be appreciated that much labor and time will be saved in the opera-

tion of the knitting machine. On half-hose machines, where the stocking is taken off of the machine at the end of knitting of the toe, it is usually necessary for the operator to manually lift the heavy wrap yarn head and to re-arrange the wrap yarns and the swinging weight therefor. This all takes time. With the improved machine the wrap yarn head automatically swings to an upward position out of the way of the cylinder and needles at the end of knitting of the stocking, and at the start of a new stocking (after the top has been placed upon the needles) it is merely necessary for the operator to knot the ends of the wrap yarns together below the improved control and guiding member K, and upon lowering of the wrap head the wrap yarns will be in position for accurate feed upon the needles of the machine when the respective wrap yarn fingers H are moved by the pattern means controlling them.

Various changes in the shape, size, and arrangement of parts may be made to the form of invention herein shown and described, without departing from the spirit of the invention or the scope of the claims.

I claim:

1. In a yarn feed and controlling mechanism for knitting machines the combination of a frame, a needle carrier, a set of needles therefor, a yarn feed member, means for moving the yarn feed member into and out of feeding relation with the needles of the machine, and means disposed at the inside of the needle line and non-movably carried directly by said frame for holding the yarn at its feed end in position to be disposed upon the needles of the machine when said yarn feed member is in feeding relation with respect to said needles.

2. In a yarn feed and controlling mechanism for knitting machines the combination of a needle carrier, a set of needles therefor, a yarn feed head including a frame having a yarn positioning portion carried in predetermined position thereby and having a portion disposed at a point below and always inside of the line of the needle hooks, a yarn feed member movably supported by the head frame having its feed end located above the normal top ends of the needles and having the yarn extending therefrom to a releasably secured position with the said yarn positioning portion which extends below the hooks of the needles, whereby upon movement of the yarn feed member the said yarn will be applied upon the needles of the machine.

3. In a knitting machine a cylinder, a set of needles for the cylinder, a yarn feed head, yarn feed fingers for the head movable over the needles to feed yarn thereto, and means consisting of an extension to the head for holding said yarns at the feed ends of the said fingers in position to insure the application of the respective yarns upon the needles when the feed fingers are moved to a yarn feeding position relative to said needles.

4. In a knitting machine the combination of a cylinder, a set of needles therefor, a yarn feed head above the cylinder, yarn feed fingers movable upon said head for application of yarns at various points about the cylinder upon the needles of the cylinder, said head having an attached yarn positioning extension below the hook ends of the needles when the head is in operative position for releasably receiving said yarns and holding them in position for feed to the needles of the machine upon movement of the yarn feed

fingers to a yarn feeding relation with said needles.

5. In a knitting machine the combination of a cylinder, a set of needles therefor, a yarn feed head above the cylinder movable towards and away from the cylinder including a frame, an extension on the frame having a portion extending when the said head is in feed relation to the cylinder to a position below the hook ends of the needles, and yarn feed fingers movably carried by said head; the yarns from said fingers at their feed ends being adapted to be extended beneath the portion of the head which extends to the position below the hook ends of the needles and there secured together in a releasable relation with respect to said extension.

6. In a knitting machine the combination of a cylinder, a set of needles therefor, a yarn feed head above the cylinder movable towards and away from the cylinder including a frame, an extension on the frame having a portion extending when the said head is in feed relation to the cylinder to a position below the hook ends of the needles, and yarn feed fingers movably carried by said head; the yarns from said fingers at their feed ends being adapted to be extended beneath the portion of the head which extends to the position below the hook ends of the needles and there secured together in a releasable relation with respect to said extension, said extension having grooves thereon for releasably holding the yarns respectively in place.

7. In a knitting machine the combination of a cylinder, a set of needles therefor, a yarn feed head above the cylinder movable towards and away from the cylinder including a frame, an extension on the frame having a portion extending when the said head is in feed relation to the cylinder to a position below the hook ends of the needles, and yarn feed fingers movably carried by said head; the yarns from said fingers at their feed ends being adapted to be extended beneath the portion of the head which extends to the position below the hook ends of the needles and there secured together in a releasable relation with respect to said extension, said extension having a peripheral series of grooves sloped to the vertical for holding the yarns respectively in place.

8. In a knitting machine a cylinder, a yarn feed head therefor, means movably mounting the yarn feed head for movement towards and away from the cylinder, means carried in predetermined position directly by said head for holding the yarns together below the normal hook ends of the needles, said yarn feed head having means for selectively moving said yarns from such position onto the needles.

9. In a knitting machine the combination of a supporting frame, a cylinder, a set of needles for the cylinder, a yarn feed head including a movable frame and movable feed fingers thereon, means for automatically moving said head towards and away from the receiving ends of the needles at predetermined operations, and means carried directly by the frame of said head for holding the yarns at their feed ends into position for feeding upon the needles of the cylinder when the respective yarn fingers are moved to apply the yarns upon the needles.

10. In a yarn feed and yarn control mechanism for knitting machines the combination of a frame, a needle carrier, a set of needles therefor, a yarn feed head having a plurality of movable yarn feed members thereon, means to move the head into and out of operative feed rela-

- tion with respect to the needles, and means carried directly by the head holding the feed ends of the yarn so that when the head is moved into an operative yarn feeding relation to the needles 5 the said yarns at their feed ends will be automatically positioned so that the feed members upon initial yarn feeding movement will apply the yarn upon the desired needle or needles.
11. In a yarn feed and yarn control mechanism for knitting machines the combination of a frame, a needle carrier, a set of needles therefor, a yarn feed head having a plurality of movable yarn feed members thereon, and means rigidly connected with the head holding the feed 10 ends of the yarn so that the said yarns at their feed ends will be positioned for application upon the desired needle or needles upon movement of the feed members into yarn feeding position.
12. In a knitting machine a cylinder, a set of 15 needles for the cylinder, a yarn feed head, yarn feed members movable upon the head for applying yarns upon the needles, and means directly connected to the head having non-movable means thereon for holding said yarns at 20 their feed ends in position to insure the application of the respective yarns upon the needles when the feed fingers are moved to a yarn feeding position relative to said needles.
13. In a knitting machine a cylinder, a set of 25 needles for the cylinder, a yarn feed head, yarn feed members movable upon the head for applying yarns upon the needles, means connected as a part of the head for holding said yarns at 30 their feed ends in position to insure the application of the respective yarns upon the needles when the feed fingers are moved to a yarn feeding position relative to said needles, the last mentioned means being non-movable and so shaped that the individual yarns will be held in definite 35 feed relation to particular needles.
14. In a knitting machine a cylinder, a feed head therefor, a plurality of yarns, yarn feed members movably carried by said head for feeding said yarns to the cylinder needles, and means 40 directly carried by said head for holding the yarns at their feed ends into such association with the cylinder needles that when the yarn feed members are moved upon the heads into a feeding position the yarns will be swung into position 45 for application upon the needles of the cylinder, said yarns at their feed ends being tied together for application upon said means just prior to the start of knitting.
15. In a knitting machine the combination of 50 a cylinder, a set of needles therefor, a yarn feed head having individually movable yarn feed members thereon, said head having a rigid extension thereon with a portion extending below the feed ends of the yarn feed members for individually holding yarn feed ends in definite feeding rela- 55
- tion with respect to the needles so that upon movement of the yarn feed members the said yarns at their feed ends will be applied upon the needles.
16. In a knitting machine the combination of 60 a cylinder, a set of needles therefor, a yarn feed head having individually movable yarn feed members thereon, said head having means thereon extending below the feed ends of the yarn feed members for individually holding the yarns in 65 definite feeding relation with respect to the needles so that upon movement of the yarn feed members the said yarns will be applied upon the needles, said means being slotted to individually place the yarns in definite relation to respective 70 needles.
17. In a knitting machine a cylinder, a circular set of needles for the cylinder, a yarn feed head above the cylinder having a plurality of 75 needles and from inside of the circular line of needles to a position outside of the circular line of needles in order to apply their respective yarns upon the needles, and means directly carried by the yarn feed head and extending to a 80 position below the hook ends of the needles and at all times inside of the circular line of needles and releasably receiving the yarns from the feed members thereon so as to position them 85 for initial application upon the needles when the yarn feed members are moved to a feeding position.
18. In a knitting machine the combination of 90 a needle carrier, a line of needles carried by the needle carrier, a yarn feeding support, a yarn feed member carried by the support and movable from a position at one side of the needle line to a position at the opposite side of the needle line for the application of a yarn upon a 95 needle or needles, and means directly carried by said support and located at all times to one side of the needle line for holding the yarn at its feed end in position for application upon the needle or needles when the yarn feed member is moved to a feeding position.
19. In a knitting machine the combination of 100 a cylinder, a set of independently movable needles upon the cylinder, means for selectively and independently moving said needles, a yarn feed head, yarn feed members movable at a location above the normal hook ends of the needles into 105 position for application of feed yarns upon the selectively elevated needles, and means directly carried by the yarn feed head for initially holding and positioning the yarns so that they 110 will be applied upon the selectively elevated needles upon movement of the yarn feed members to feeding position.

HARRY MCADAMS. 60
